ELECTRIC WIRE TAP

Filed June 9, 1927

LOUIS LUDWIG.
INVENTOR.

BY
J. Stuart Schaff
ATTORNEY.

UNITED STATES PATENT OFFICE.

LOUIS LUDWIG, OF BROOKLYN, NEW YORK.

ELECTRIC WIRE TAP.

Application filed June 9, 1927. Serial No. 197,662.

The object of this invention is to provide a tap for electric wires.

A further object of this invention is to provide a tap which pierces the electric wires 5 for making electrical connection.

A particular object of this invention is to provide a tap for electrical wires, the tap having piercing elements which are fixed.

10 With these and other objects in view, the invention consists in the novel combination and arrangement of parts which will be fully set forth in the following specification and accompanying drawing, in which:

15 Fig. 1, is a top view of the tap.

Fig. 2, is a cross-sectional view of the tap.

Fig. 3, is a bottom view of the tap.

Figure 4 is a section taken on line 4—4 20 Figure 2.

In the drawing the numeral 1, indicates the body of the tap, which is made of any composition bakelite or the like, the tap is molded with two channels 2 and 3 in the upper end, the body 1 has the projections 4, 5, 25 and 6, the projections 4 and 6 are inclined.

A tip 7 of the same material is molded to fit over the body 1, having cooperating inclined sides 8 and 9 and a channel 5^a to receive the projection 5.

The bottom of the body 1 is provided with two slots 9 and 10. A projection 11, extends through the center forming the division wall.

35 Through the body 1 two bushings 12 and 13 are fixed either by being molded in or threaded into the body 1. The inside of each bushing forming a screw socket by having one end or the bottom internally thread-

40 ed, while the other end is formed solid and pointed as at 14 and 15. Screws 16 and 17 are threaded into the bushings 12 and 13, these screws extend into the slots 9 and 10.

The bushings are set so that the points extend almost the entire height of channels 45 2 and 3.

The center of the body 1 is bored and a stem or rod 18 extends therethrough, the stem is threaded or otherwise fixed into the tap 7. The other end of the stem is provided with threaded flat head 19, a spring 20 seated in the projection 11 of the body 1 tends to force the flat head away from the body 1 at the same time drawing the tip 7 towards the body 1.

50 In operation, when a connection is desired to the main line, the wires from the article to be connected are fastened on the screws 16 and 17 and the flat head is pushed in, and each main wire is forced in the grooves 2 and 3 and the flat head let loose, the spring 20 forces the tip in and the points 14 and 15 pierce the main wires, thus forming a direct connection through the metal bushing with the screws and the wires to the article to be 55 supplied with electricity.

55 While in the foregoing there has been shown and described the preferred embodiment of this invention, it is to be understood that such changes may be made in the combination and arrangement of parts as will fall within the spirit and scope of the invention as defined in the appended claim.

What I claim is:

60 In a device of the class described, a body, channels at one end of the body for receiving main wires, slots at another part of the body for receiving connecting wires which are to be in electrical connection with the main wires, sharp pointed bushings fixed 65 in the body for piercing the insulation of the main wires and forming metallic contact with the main wires and screws threaded within the bushings for forming electrical contact with the connecting wires, and means for holding the main wires in the channels.

65 Signed at Brooklyn, New York, in the county of Kings and State of New York this 20th day of May, A. D. 1927.

LOUIS LUDWIG.
